- The ornamental design for a movable handle for endoscopic vessel sealer and divider, as shown and described.
- DESCRIPTION**
- FIG. 1 is a right, front, perspective view of a movable handle for endoscopic vessel sealer and divider in accordance with the present design;

FIG. 2 is a right, side view of the movable handle for endoscopic vessel sealer and divider of FIG. 1;
FIG. 3 is a front view of the movable handle for endoscopic vessel sealer and divider of FIG. 1;
FIG. 4 is a left, rear, perspective view of the movable handle for endoscopic vessel sealer and divider of FIG. 1; and,
FIG. 5 is a right, side, cross-sectional view of the movable handle for endoscopic vessel sealer and divider of FIG. 1.
